(No Model.)

J. RANDOLPH.

PAPER HANGER.

No. 369,029.

Patented Aug. 30, 1887.

UNITED STATES PATENT OFFICE.

JOSEPH RANDOLPH, OF PEWAMO, MICHIGAN, ASSIGNOR TO THE PEWAMO MANUFACTURING COMPANY, OF SAME PLACE.

PAPER-HANGER.

SPECIFICATION forming part of Letters Patent No. 369,029, dated August 30, 1887.

Application filed March 31, 1887. Serial No. 233,206. (No model.)

To all whom it may concern:

Be it known that I, JOSEPH RANDOLPH, a citizen of the United States, residing at Pewamo, in the county of Ionia and State of Michigan, have invented a new and useful Improvement in Paper-Hangers, of which the following is a specification.

My invention relates to an improvement in paper-hangers; and it consists in the peculiar construction and combination of devices, that will be more fully set forth hereinafter, and particularly pointed out in the claims.

In the drawings, Figure 1 is a side elevation of a paper-hanger embodying my improvements. Fig. 2 is a rear elevation of the same. Fig. 3 is a vertical section on the line $x-x$ of Fig. 2. Fig. 4 is a detailed top plan view of a portion of the paper-hanger.

A represents a standard or handle, which is 20 of suitable length.

B represents the head of the paper-hanger, the construction of which is as follows: C represents a cross-bar, which is provided at its center with an annular groove, D. To the 25 ends of the cross-bar are secured springs E, having the arms F and G. The latter arm, G, is provided with spring-coils G', and the spring-arms F and G normally move toward each other. To the outer ends of the arms F 30 is secured a jaw, H, which is arranged parallel with the cross-bar C, and to the front edge of the said jaw is secured a projecting guard, I, which is made of bent wire of suitable thickness. The ends of the said guard are provided 35 with eyes K, and screws L pass through the said eyes, and thus secure the guard to the jaw, so that the guard can be removed from the jaw when desired.

L represents a jaw, which is secured to the 40 free ends of the spring-arms G. This jaw L is normally pressed by the said spring-arms against the opposing sides of the jaw H, thus enabling the head of the paper-hanger to clamp one end of a piece of wall-paper between 45 the said jaws.

To the under side of the jaw H is journaled a longitudinal rock-shaft, M, which is provided at its extremities with bent arms N, that bear against the spring-arms G, near the outer 50 ends of the latter. At the center of the rock-

shaft is formed a forward-projecting lever-arm, O.

P represents an operating-cord which is attached to the said lever-arm.

From the foregoing description it will be 55 readily understood that by drawing down upon the cord the rock-shaft will be turned rearward on the jaw H, so as to cause the arms N to bear rearward against the spring-arms G, and thus move the jaw L from the jaw H, so as to 60 release the wall-paper after it has been pasted to the wall.

V represents a clamp-bolt, which extends through the transverse opening in the upper end of the standard A, and has its rear end 65 bent into semicircular form to form a clamping-arm adapted to enter the annular groove D of the cross-bar.

W represents a cylindrical sleeve, which is made of metal and has its rear edge concave, 70 and thereby adapted to fit snugly against the rounded central portion of the cross-bar. The front side of the said sleeve is provided with a radial series of teeth or serrations, W'.

X represents a circular washer having a 75 central opening through which the clamping-bolt V extends. The said bolt also passes through a central opening made in the sleeve. The washer is provided on its rear side with a series of radial serrations or teeth that coincide with the teeth or serrations W', and the front side of the washer is provided with projecting lugs X', that enter recesses in the rear side of the standard and prevent the washer from turning thereon. The front end of the 80 clamping-bolt V is provided with screw-threads, and a thumb-nut, Y, is screwed to the front end of the said bolt, thereby clamping the sleeve firmly to the washer and clamping the cross-bar firmly against the rear side of 85 the sleeve. By loosening the thumb-nut Y the pressure of the clamping-bolt will be relaxed sufficiently to enable the cross-bar C to be turned in the rear end of the bolt, so as to adjust the head to any desired angle. 90

The toothed washer and sleeve permit the head to be turned on the end of the standard to any desired angle and clamped therein, the clamping-bolt V being the axis for the head. 95

The function of the wire guard on the head 100

is to prevent the paper from coming in contact with the wall and sticking thereto until the paper is adjusted to the desired place. This guard is used only when hanging paper to the 5 wall; but when paper is to be pasted to the ceiling the guard is detached from the head.

Having thus described my invention, I claim—

1. In a paper-hanger, the head having the 10 spring-actuated clamping-jaws H and L and the guard I, attached to one of the said jaws and projecting from the frontside thereof, substantially as described.

2. In a paper-hanger, the combination of the 15 standard A, the sleeve W, pivoted thereto and projecting at right angles therefrom, and the head carrying the clamping-jaws and having the cross-bar C, pivoted in the sleeve and arranged at right angles thereto, whereby the 20 clamping-head may be turned in any desired direction, substantially as described.

3. In a paper-hanger, the combination of the 25 cross-bar C, the spring-arms F and G, projecting from the ends thereof, the jaw H, attached to the free ends of the arms F, the jaw L, attached to the free ends of the arms G, and the rock-shaft journaled to the jaw H, and having the arms bearing against the spring-arms G, whereby when the rock-shaft is turned the 30 jaws will be forced apart, for the purpose set forth, substantially as described.

4. In a paper-hanger, the combination of the 35 head having the spring-actuated clamping-jaws and the guard I, detachably secured to one of the said jaws and projecting from the front side thereof, for the purpose set forth, substantially as described.

5. In a paper-hanger, the combination of the 40 head having the spring-actuated clamping-jaws, the standard or handle A, the clamping-bolt V, extending through the head and having

the eye at its rear end to which the head is secured, whereby the said head may be turned in the said eye, and means, substantially as set forth, to clamp the head to the standard 45 at any desired inclination, substantially as described.

6. The combination, in a paper-hanger, of the head having the cross-bar C, provided with the annular grooves D, the clamping-bolt V, 50 having its rear end curved in the groove D, the sleeve W, bearing against one side of the cross-bar and strung on the clamping-bolt, the head having the transverse opening through which the bolt extends, the washer strung on the 55 bolt and having the teeth to fit corresponding teeth on the opposing face of the sleeve, and the clamping-nut Y, screwed on the front end of the bolt, whereby the head may be adjusted to any desired inclination on the standard in 60 either direction, substantially as described.

7. In a paper-hanger, the clamping-head comprising the cross-bar C, the spring-arm F, projecting therefrom, the jaw H, attached to the outer ends of the said spring-arms, the 65 spring-arms G, projecting from the cross-bar, and having the coils G, and the jaw L, attached to the outer ends of arms G, substantially as described.

8. In combination with the spring-actuated 70 jaws, the rock-shaft M, journaled to one jaw and having detent-arms N to engage the other jaw, and the operating means for the rock-shaft, as set forth.

In testimony that I claim the foregoing as 75 my own I have hereto affixed my signature in presence of two witnesses.

JOSEPH RANDOLPH.

Witnesses:

M. L. DIVER,
JAY HOWARD.
